UNITED STATES PATENT OFFICE.

CHARLES F. G. STENDER, OF CHICAGO, ILLINOIS.

HARNESS-PAD.

SPECIFICATION forming part of Letters Patent No. 453,249, dated June 2, 1891.

Application filed March 15, 1890. Serial No. 344,043. (No model.)

To all whom it may concern:

Be it known that I, CHARLES F. G. STENDER, a citizen of the United States, residing in Chicago, in the county of Cook, and State of Illinois, have invented a new and useful Improvement in Harness-Pads, of which the following is a specification.

My invention relates to improvements in harness-pads, and more particularly to improvements in the filling or packing for pads of harness saddles or trees. Heretofore in the manufacture of these pads the leather covering or bottom piece of the pad has been first tacked or otherwise secured to the leather nut-piece and then the packing or filling, consisting usually of hair, has been stuffed in through an opening left at the end. Pads of this construction must each be separately made, and it is difficult to pack the hair or filling material into the leather shell so as to give a smooth, uniform, and proper shape to the finished pad, and the pads so constructed are liable to lose their shape when subjected to wear or when exposed to dampness. These pads are also of a comparatively expensive construction, each having to be separately and individually made and requiring skilled labor.

The object of my invention is to provide a harness-pad of a simple, efficient, and durable construction, having the requisite flexibility and elasticity, which will not be injured or misshapen by wear or exposure, and the filling or packing material of which may be shaped prior to its insertion in the leather case or shell of the pad, so that the pads may be manufactured very rapidly and cheaply.

To this end my invention consists of a pad for use on harness-saddles and trees or for other purposes, consisting of a leather case or shell and a flexible elastic filling molded to shape. The flexible elastic filling I make or prefer to make of papier-maché or paper-pulp or other analogous material. The papier-maché is first pressed in a moist condition into a mold conforming in shape and size to the pad desired to be made. The molded papier-maché filling is then dried in any suitable manner. To insert it in its leather case or shell, I prefer to place the bottom piece or flexible leather covering of the pad in a mold corresponding in shape to the pad. I then place the flexible

molded filling in the mold inside such leather covering, and then, after pressing or hammering the two snugly together into place in the mold, I put the top piece of the pad in place and tack or otherwise secure the bottom or covering piece thereto. My flexible molded pad-fillings may be manufactured in quantities, and, as they retain their shape perfectly when dried, they may be kept for any length of time and sold and shipped as an article of manufacture for use by harness-makers.

In the accompanying drawings, which form a part of this specification, and in which similar letters of reference indicate like parts, Figure 1 is a side elevation of a device embodying my invention as applied to an ordinary harness saddle or tree. Fig. 2 is a detail side view of the flexible molded filling for the pad. Fig. 3 is a plan view of the same. Fig. 4 is a cross-section on line 4-4 of Fig. 2. Fig. 5 is a longitudinal section of a mold which may be used in the manufacture of the pad for closing the bottom piece or covering of the pad around the flexible molded filling. Fig. 6 is a perspective view of a mold suitable for use in making or molding the papier-maché filling.

It will be understood, however, that my improved flexible molded pad-filling may be used in the manufacture of other pads or pads of different form than that shown in the drawings.

In the drawings, A represents the metal plate of the saddle or tree, A' A' the turrets, and A² the hook of an ordinary harness saddle or tree.

B is the flexible bottom or leather covering of the pad.

C is the leather nut-piece, usually made of sole-leather, and C' is the re-enforcing strip usually employed beneath the nut-piece.

D is the flexible molded filling, made, preferably, of papier-maché or similar pulp. The filling D is molded to the required shape in a suitable mold, as E, while the paper-pulp is in a moist condition, and then, after being thus pressed into the mold and molded to the shape required, the filling D is next dried. When thus dried, it will perfectly retain its shape, and at the same time be sufficiently flexible and elastic to make a proper filling or packing for pads. As the filling D is

formed or shaped by pressing the papier-maché or pulp into a smooth mold, it is obvious that the pad-filling D will have a perfectly smooth surface, and that the pads may be made of a 5 perfectly smooth and uniform shape. After the pad-fillings D are thus dried the bottom piece or covering B of the pad is placed in a suitable mold, as E. Then the molded filling D is inserted in the mold within the bottom 10 piece B, and then, the nut-plate or covering-plate C, with the re-enforcing plate C', being put in place and pressed or hammered firmly down, the edges of the covering-piece B are tacked down or otherwise secured to the nut-piece C. In this way the pads may be very 15 rapidly and cheaply manufactured, and the pads when constructed will be flexible and of a perfectly smooth and uniform shape and will not be liable to lose their shape or form 20 by wear or exposure.

The same mold which is used for molding or shaping the filling D may also be used in the manufacture of the pad, as the filling D will shrink somewhat in drying.

I have shown and described my invention 25 as applied to the manufacture of harness-pads of the particular kind or class shown in the drawings; but I desire it to be understood that my invention may be applied to the manufacture of other shapes and kinds of 30 harness-pads.

I claim—

The combination, in a harness-pad, of the 35 flexible leather bottom piece or covering B with a light flexible molded fibrous filling D, of pulp or papier-maché and nut-piece C, said flexible bottom piece B being folded around said flexible fibrous molded filling D and having its edges secured to said nut-piece C, and said filling D being adapted to yield or bend 40 without granulating, cracking, or breaking, substantially as specified.

CHAS. F. G. STENDER.
